OIL-RECTIFYING APPARATUS.

Application filed August 3, 1925. Serial No. 47,927.

The invention relates to oil rectifying apparatus and is particularly applicable to internal combustion engines. One of the objects of the invention is to provide a simple and efficient unit for removing water, gasoline and other foreign material from the oil. Other objects of the invention are to provide an oil rectifying apparatus, which is dependent upon heat for its purifying operation and which is so arranged that the oil may flow therethrough in the event that the heat to which the oil is subjected is not sufficient to effect the purifying operation; the provision of an oil rectifying apparatus having an oil receiving chamber and a heating chamber below and communicating with the oil receiving chamber, the heating chamber having a double wall in its upper portion for producing a heat insulation effect; the provision of a discharge passageway extending from the heating chamber through the receiving chamber to a point thereabove, this discharge passageway being insulated from the oil in the receiving chamber; the provision of heat radiating fins around that portion of the body having the heating chamber for maintaining the oil in the receiving chamber relatively cool; the provision of a condensing chamber above the receiving chamber and communicating with the heating chamber and a spreader for the oil above the receiving chamber and arranged so that oil overflowing the spreader drops into the oil in the receiving chamber prior to its discharge; the provision of a simple form of filter for the oil passing to the receiving chamber; and the provision of a valve for variably controlling the flow of oil into the receiving chamber. Further objects of the invention are the provision of a cooling device for the oil after it leaves the receiving chamber and a by-pass for the cooling device which is adapted to conduct the oil in the event that the oil in the cooling device has a sluggish action owing to being congealed or for other reasons; the provision of a thermostatic control device for controlling the heat conducted to the heating chamber; the provision of means operable from the throttle valve for controlling the flow of exhaust gases past the heating chamber; and the provision of deflecting means in the pipe, which is adapted for the passage of the exhaust gases, this deflecting means controlling the contact of the exhaust gases with the member containing the liquid to be vaporized.

With these as well as other objects in view the invention resides in the novel features of construction and combinations and arrangements of parts as more fully herein-after set forth.

In the drawings:

Figure 1 is a sectional side elevation of an internal combustion engine having applied thereto an oil rectifying apparatus embodying my invention; 65

Figure 2 is a plan view of a portion thereof; 70

Figure 3 is a front elevation thereof;

Figure 4 is a cross section on the line 4—4 of Figure 3;

Figure 5 is a cross section on the line 5—5 of Figure 4; 75

Figure 6 is a view similar to Figure 4 and showing a modified construction;

Figure 7 is a cross section on the line 7—7 of Figure 6;

Figure 8 is a partial view similar to Figure 4 and showing a modified construction of inlet; 80

Figure 9 is a cross section on the line 9—9 of Figure 1;

Figure 10 is a sectional elevation showing the method of controlling the contact of the exhaust gases with an intake manifold of an internal combustion engine; 85

Figure 11 is a cross section on the line 11—11 of Figure 10; 90

Figure 12 is a view similar to Figure 11 and showing a modified construction;

Figure 13 is a similar view showing another modified construction.

1 is an internal combustion engine and 2 are respectively the intake and exhaust manifolds. 4 is a usual construction of fan in advance of the engine. 5 is the oil rectifying device located in rear of the fan 4 and secured upon the pipe 6 which communicates with the exhaust manifold and is adapted for the passage of the exhaust gases. 100

The body of the oil rectifying device has the upper chamber 7 for receiving the oil to be rectified, the lower chamber 8 below 105 and communicating with the upper chamber

7 for heating the oil and the condensing chamber 9 above the upper chamber 7. The upper chamber 7 has the inlet 10 which is in communication with the source of supply 5 for the oil such as the gear pump 11. This upper chamber also has the overflow outlet 12 for the oil. The lower chamber 8 communicates with the lower portion of the upper chamber 7 through the passageways 13, 10 14, 15, 16 and 17, there being a check valve in the passageway 16 which permits the flow of the oil from the upper chamber to the lower chamber, but prevents its return flow. As shown particularly in Figure 5 this check 15 valve comprises the tube 18 located in the vertical passageway 16, a ported member 19 seating against the lower end of the tube and extending upwardly therewithin and having the central opening 20, a disk valve 21 located within and movable longitudinally of the tube and having the peripheral projections 22 and the abutment member 23 seated against the upper end of the tube and extending downwardly therewithin and having 25 the central opening 24. This abutment member limits the upward movement of the disk valve and is provided with the vertical slots 25 in its lower portion for permitting the flow of oil therethrough when the disk 30 valve is seated thereagainst. 26 is a suitable support having upwardly extending prongs engageable with the ported member 19 for supporting this member, the tube and upper abutment member within the passageway. It will be seen that with this construction oil may pass upwardly through the ported member 19 raising the disk valve of this ported member, pass between the main body of the disk valve and the tube 35 18, through the spaces afforded by the projections 22 and then through the vertical slots 25 in the upper abutment member 23 and into the passageway 17, after which it enters the lower chamber 8. The lower portion 40 of the body of the oil rectifying device is provided with a flange which is adapted to be seated upon and secured to the upper wall of the pipe 6. The lower chamber 8 is formed by the lower portion of this body 45 and by means of the shell 27 secured to the body and extending downwardly into the pipe 6. 28 is a bell-shaped partition in the lower portion of the lower chamber and having its depending flanges terminating a 50 slight distance from the side wall of the shell 27. This partition forms with the bottom of the shell a space for highly heating the oil therewithin. 29 is a tube opening at its lower end into the space below the partition 28, this tube extending upwardly 55 through the upper portion of the lower chamber 8 and also through the upper chamber 7 and having an upper open end terminating above the level of the oil in the upper chamber.

To maintain the oil in the upper chamber 7 relatively cool, that portion of the body of the oil rectifying device having the upper chamber therewithin is formed with the heat radiating fins 30 which afford an extended 70 surface for contact with the air forced rearwardly by means of the fan 4. Furthermore the upper portion of the lower chamber 8 is heat insulated, this being effected in the present instance by means of the bell 31 75 which is secured upon the tube 29 and has its top spaced slightly from the top of the lower chamber and its side wall spaced slightly from the side wall of the lower chamber. That portion of the tube 29 extending upwardly to the upper chamber 7 is also heat insulated by means of the tube 32 surrounding and slightly spaced from the tube 29 and extending from the bottom of the upper chamber to a point substantially 85 even with the top of the tube 29.

To freely permit the oil to enter the lower chamber 8 the upper portion thereof is vented by means of the opening 33 in the tube 29, this opening communicating with the annular space 34 formed by the ring 35 which surrounds the tube 29 and holds the bell 31 in place. This ring has the opening 36 therein for placing the annular space 34 in communication with the upper portion of 90 the lower chamber.

37 and 38 are deflectors above the upper chamber 7. The deflector 37 is located directly above the open end of the pipe 29 and the deflector 38 is located above the deflector 37. The latter deflector normally forms the bottom of the condensing chamber and is adapted to normally seat upon the annular flange 39 of the body of the oil rectifying device and is held to its seat by means of the coil spring 40 which surrounds the shoulder rivet 41 extending through the deflector 38 and carrying the deflector 37 and carried in turn by means of the cover 42 upon the body of the oil rectifying device. 43 is a spreader in the nature of a shallow cup mounted upon the upper end of the tube 29 and having upstanding legs 44 engageable with the under side of the deflector 38 for holding the spreader in place. This spreader is located within the confines of the upper chamber 7 and above the level of the oil therewithin and is adapted to receive the oil, including the foreign material therein, after it passes upwardly through the tube 29 and is deflected downwardly to spread this oil and allow the foreign material, such as water and gasoline, to evaporate, the vapor then passing upwardly through the openings 45 in the deflector 38 and into the condensing chamber 9 after which it passes outwardly through the openings 46 formed at the sides of the body of the device. Oil overflowing the spreader 43 drops down into the oil in the upper chamber 7 and commingles there- 100 105 110 115 120 125 130

with prior to its discharge through the overflow outlet 12.

To permit the oil circulating through the upper chamber 7 and heating chamber when the temperature in the heating chamber is not sufficient to boil the oil and eject the same upwardly above the upper end of the tube 29, I have provided the by-pass 46' in the nature of a tube extending laterally from 10 and communicating with the tube 29 and with the discharge nipple 47 of the body of the oil rectifying device. This by-pass is located below the overflow outlet 12 and does not hinder the discharge of the oil and foreign materials upwardly through the tube 29 under the pressure generated by heat when the latter is sufficient.

For the purpose of collecting sediment, I have provided at the inlet 10 for the upper 20 chamber 7 the filter device 48 which has the fine mesh screen or filter 49 forming a transverse partition within its chamber. This screen is provided in its upper portion with the opening 50 for the passage of the oil 25 when the latter has raised sufficiently in the chamber of the filter device. The pin 51 is preferably provided extending through the opening 50 for locating the opening in the upper portion of the chamber. If desired, 30 a valve 52 may also be provided surrounding the pin and adapted to close the opening 50, this valve being forced against the screen by suitable means such as the coil spring 53.

To provide a restricted opening in the 35 inlet 10, there is the cup-shaped valve 54 located within this inlet and having the restricted opening 55 in its base. To maintain this opening free of sediment there is the pin 56 which is held stationary and which is 40 adapted to extend through the opening 55 when the valve 54 is forced rearwardly by the oil passing through the inlet. The valve is normally held in predetermined relation to the pin by means of the coil spring 57. 45 To variably control the flow of the oil passing through the inlet 10 according to the pressure of the oil, the pin 56 is tapered so that as the valve is forced rearwardly the effective area of the opening 55 is gradually 50 decreased.

For the purpose of cooling the oil I have provided the cooling device 58 preferably formed of a copper tube and having the upstanding legs 59 and 60, the leg 59 being 55 coiled around the leg 60. The leg 59 as shown in the present instance is connected to the discharge nipple 47 of the body of the oil rectifying device and the leg 60 is connected to the crank case of the engine. This 60 cooling device is located in rear of the fan 4, which directs air against and past the same. In the event that there is no flow of the oil through the cooling device or its flow is sluggish owing to the oil being congealed, 65 or for some other reason, oil may flow

through the by-pass 61 which is in the nature of a tube extending from the upper end portion of the leg 59 and into the upper end portion of the leg 60 at a lower point. This tube preferably has a portion extending immediately adjacent to the pipe 6 to further increase the temperature of the oil flowing therethrough. Thus it will be seen that with this arrangement the oil may be cooled in the summer time or when hot and may be 70 heated in the winter time when cold so that a more uniform temperature of the oil passing to the working parts of the engine may be secured, regardless of the temperature of the air. 75

As shown in the modified construction in Figures 6 and 7 the air rectifying device has the same general arrangement of parts and communications with the exception that the heating chamber 62 in the lower portion of 80 the body of the device does not extend downwardly into the pipe 63 adapted for the passage of the exhaust gases. Instead the shell 64 forming the lower portion of the heating chamber extends upwardly into the body and 85 the discharge pipe 65 leading from the heating chamber opens directly into this heating chamber. To control the amount of heat to which the heating chamber is exposed in this construction I have provided the thermostatic control device 66 which extends into the pipe 63 and is in heat conducting contact with the shell 64. This device comprises the stem 67 threaded into the shell and extending downwardly therefrom into 90 the pipe. This stem is provided with the spaced lateral fins 68 preferably integral therewith. 69 is a cage surrounding the stem 67 of the heat conducting chamber and provided with the spaced lateral deflectors 95 70 which are connected together by the vertical ribs 71 carried upon the base 72, these deflectors being adapted to laterally align with the fins 68. The base 72 is connected to the lower end of the thermostat 73 which 100 is located within the stem 67 and is rigidly connected at its upper end to the stem. With this arrangement as the temperature of the exhaust gases increases the thermostat 105 expands, thereby lowering the cage and moving the deflectors downwardly between the fins to restrict the flow of the exhaust gases past the fins. The heat is conducted from these fins through the stem 67 into the shell. 110

In the modified construction shown in 115 Figure 8 the inlet 74 in the body of the oil rectifying device has the restricted opening 75 opening into the upper chamber 76 of this body. 77 is a vertically movable valve located within the inlet and having the annular groove 78 normally registering with the opening 75. The portion of this valve below the annular groove is provided with vertical grooves 79 to allow the oil to pass downwardly below the valve and to raise the valve 120 125 130

upon excessive pressure of the oil against the pressure of the coil spring 8 within and abutting the valve to thereby shut off a portion of the opening 75 and restrict the effective area thereof. With this construction it will be seen that the flow of the oil into the upper or oil receiving chamber is varied according to the pressure of the oil passing through the inlet.

For the purpose of controlling the heating of the lower or heating chamber of the body of the oil rectifying device by the exhaust gases according to the flow of these exhaust gases passing through the pipe 6, I have provided as shown in Figures 1 and 9 particularly, the V-shaped deflector 81 facing the flow of exhaust gases and located in advance of the heating chamber and spaced slightly therefrom. This deflector is in the nature of a lug preferably formed integral with the pipe 6 and is so constructed that it tends to laterally deflect the exhaust gases from the heating chamber to a greater extent as the velocity of these exhaust gases increases, thereby reducing the contact of the exhaust gases with the heating chamber as their velocity increases.

To control the flow of the exhaust gases through the pipe 6 I have provided the pivotal valve 82, which is adapted to extend partially across the entrance end of the pipe 60 or the discharge end of the exhaust manifold 3. This valve is preferably connected to the throttle valve 83 in the intake manifold to be operated upon movement of the latter, the connection being such that as the throttle valve is opened, the valve controlling the flow of the gases through the pipe 6 is closed to limit the flow of the exhaust gases therethrough. As diagrammatically shown in Figure 1, 84 is an arm connected to the valve 82, 85 is an arm connected to the valve 83 and 86 is a tie rod pivotally connecting these two arms together.

As shown in Figures 10, 11, 12 and 13, the contact of a heating medium such as exhaust gases with a member containing liquid particles other than the heating chamber of an oil rectifying device may be controlled according to the velocity of the heating medium to thereby control the heat to which this member is subjected. In Figures 10, 11 and 12, 87 is a carburetor, 88 an intake manifold connected to the carburetor and extending upwardly therefrom. 89 is a pipe adapted to conduct exhaust gases, the intake manifold extending through this pipe. 90 is the deflector which is V-shaped and faces the flow of the exhaust gases and is located in advance of and slightly spaced from the intake manifold, this deflector being in the nature of a rib preferably formed integrally with the pipe 89 and extending parallel to the intake manifold 88. To additionally control the contact of the exhaust gases with

the intake manifold I have as shown in Figure 12 provided the additional deflectors 91, which extend inwardly from opposite sides of and slightly in rear of the middle of the intake manifold and are adapted to prevent the exhaust gases from passing inwardly toward the intake manifold when passing through the pipe at high velocity. However, when the exhaust gases are passing through the pipe at a lower velocity some of these exhaust gases may pass between these deflectors and intake manifold. As shown in Figure 13 the intake manifold 92 extends transversely of the pipe 93 adapted for the passage of the exhaust gases and extends inwardly into a side of this pipe. 94 is a deflector located in advance of the intake manifold and extending slightly thereover, this deflector being preferably a lug formed integrally with the pipe 93. With this construction it will be seen that as the velocity of the exhaust gases passing through the pipe 93 increases, the contact of these exhaust gases with the intake manifold decreases.

What I claim as my invention is:

1. In an oil rectifying apparatus, a body having in combination an oil receiving chamber provided with an inlet and an overflow outlet, and a heating chamber communicating with said receiving chamber at a point below the level of said overflow outlet, said heating chamber being provided with an outlet for the vaporized contents in the oil above the level of said first-mentioned overflow outlet and with an overflow outlet for the oil below the level of said first-mentioned overflow outlet and above the level of said point of communication of said heating chamber with said receiving chamber.

2. In an oil rectifying apparatus, a body having in combination an oil receiving chamber provided with an inlet and an overflow outlet, a heating chamber communicating with said receiving chamber at a point below the level of said overflow outlet, said heating chamber being provided with an outlet for the vaporized contents in the oil above the level of said first-mentioned overflow outlet and with an overflow outlet for the oil below the level of said first-mentioned overflow outlet and above the level of said point of communication of said heating chamber with said receiving chamber, and heat radiating fins upon the portion of said body having said receiving chamber.

3. In an oil rectifying apparatus, a body having in combination an oil receiving chamber provided with an inlet and an overflow outlet, a heating chamber below said receiving chamber and communicating therewith at a point below the level of said overflow outlet, a condensing chamber above said receiving chamber, means forming a passageway extending between said heating and

receiving chambers and communicating with the latter above the level of oil therewithin, and means forming an overflow outlet connecting into said passageway forming means 5 and located below the level of said first-mentioned overflow outlet and above the point of communication of said heating and receiving chambers.

4. In an oil rectifying apparatus, a body 10 having in combination an oil receiving chamber provided with an inlet and an overflow outlet, a heating chamber below said receiving chamber and communicating therewith at a point below the level of said overflow 15 outlet, a condensing chamber above said receiving chamber, a discharge tube extending between said heating and receiving chambers and communicating with the latter above the level of oil therewithin, and a bypass tube communicating with said discharge tube and located at a point below the level of said first-mentioned overflow outlet and above the level of the point of communication between said heating and receiving 20 chambers.

5. In an oil rectifying apparatus, a body 25 having in combination an oil receiving chamber provided with an inlet and an overflow outlet, a heating chamber below said receiving chamber and communicating therewith at a point below the level of said overflow outlet, a condensing chamber above 30 said receiving chamber, means forming a passageway extending within said receiving chamber and communicating with said heating and receiving chambers, means for insulating said passageway forming means from the oil in said receiving chamber, and means forming a by-pass communicating 35 with said passageway forming means and located at a point below the level of said overflow outlet and above the level of the point of communication of said heating and receiving chambers.

45 6. In an oil rectifying apparatus, a body having in combination an oil receiving chamber provided with an inlet and an overflow outlet, a heating chamber below said oil receiving chamber and communicating therewith at a point below the level of said overflow outlet, a condensing chamber above 50 said receiving chamber and communicating therewith, a tube extending within said receiving chamber and having lower and upper ends 55 communicating respectively with said heating and receiving chambers, a second tube surrounding and spaced from the portion of said first-mentioned tube extending within said receiving chamber, and a bypass tube extending laterally from said first-mentioned tube and communicating therewith and located at a point below the

level of said overflow outlet and above the point of communication of said heating and receiving chambers.

7. In an oil rectifying apparatus, a body 65 having in combination an oil receiving chamber, a heating chamber communicating with said receiving chamber and adapted to receive the oil therefrom, a condensing chamber above said receiving chamber, a tube forming a discharge passageway extending within said receiving chamber and communicating with said heating and receiving chambers, and means for insulating said tube 70 from the oil in said receiving chamber.

8. In an oil rectifying apparatus, a body 75 having in combination an oil receiving chamber, a heating chamber below said receiving chamber, means forming a passageway for oil from the lower end of said receiving chamber to said heating chamber, a check valve in said passageway for preventing the return of the oil, a tube extending within said receiving chamber and having open lower and upper ends respectively 80 within said heating and receiving chambers, and a lateral by-pass tube opening into said first-mentioned tube near the upper end of said receiving chamber.

9. In an oil rectifying apparatus, a body 85 having in combination an oil receiving chamber and a heating chamber communicating with said receiving chamber and having its lower portion in contact with a heating medium, a partition within the lower portion of said heating chamber and forming a space therebelow in communication with the upper portion of said heating chamber, and means forming a discharge passageway 90 communicating with the space below said partition and extending above the level of the oil in said receiving chamber.

10. In an oil rectifying apparatus, a body 95 having in combination an oil receiving chamber and a heating chamber below and communicating with said receiving chamber, means forming a discharge passageway from said heating chamber to a point above the level of the oil in said receiving chamber, and means providing heat insulation for the portion of said heating chamber adjacent to said receiving chamber.

11. In an oil rectifying apparatus, a body 110 having an oil receiving chamber and a heating chamber below and communicating with said receiving chamber, said heating chamber having spaced walls in its upper portion providing heat insulating space, and means forming a discharge passageway from 115 said heating chamber to a point above the oil in said receiving chamber.

In testimony whereof I affix my signature.
PHELPS M. FREER.
